Company, Brooklyn, N. Y.

Application February 4, 1936, Serial No. 62,238

4 Claims. (Cl. 66—178)

This invention relates to a stocking, more particularly to a combination stocking leg and boot, and has for its primary object the production of a stocking that, from outward appearances, in-
5 corporates a boot drawn over a silk stocking.

An object of the invention resides in the novel manner of producing the leg portion of the stocking from sheer fabric, and producing the boot of the stocking from a more or less opaque fabric, thereby establishing a contrast between the two 10 fabrics for producing the visible effect of a boot applied to a complete sheer stocking.

Another object of the invention resides in producing the leg of the stocking from a sheer chiffon fabric and producing the boot as a continuation thereof, formed from a heavier fabric, provisions being made to enable the cutting away of the leg fabric so that the boot may be used alone, in case the leg fabric develops "runs", or 20 is rendered unwearable due to any other defects.

A feature of the invention resides in knitting the major portion of the leg of the stocking from silk yarn and the boot of the stocking from a dissimilar yarn, such as cotton, thereby presenting a visible contrast between the leg and boot and, further, giving the boot greater strength than 25 is possessed by the leg fabric.

Another feature of the invention resides in the novel method of knitting the stocking so that 30 the boot and leg fabrics may be knitted as a continuous length of fabric with a cuff arranged at the point of juncture of the boot and leg fabrics.

Besides the above, the invention is distinguished in the method of knitting a stocking 35 with a leg fabric knitted from silk yarn, a boot fabric knitted from a dissimilar yarn, such as cotton, and topping back upon the needles of the knitting machine a portion of the boot fabric so that a cuff will be formed at the point of juncture of the boot and leg fabrics.

The invention is further distinguished in the use of a leg fabric and a boot fabric, formed from dissimilar materials and united in such a manner as to produce a cuff at the point of juncture 45 thereof, and further, enabling the leg fabric and the boot fabric to be made on either a full fashioned knitting machine or a circular knitting machine.

The invention is further distinguished in the use of elastic elements in the cuff so as to enable 50 the cuff to properly cling about the leg of the wearer in the use of the stocking.

With these and other objects in view, the invention will be better understood from the fol-

lowing detailed description, taken in conjunction with the accompanying drawings, wherein:—

Figure 1 is a side elevation of a full fashioned stocking constructed in accordance with our invention. 5

Figure 2 is a group view of the leg blank and the foot blank.

Figure 3 is a diagrammatic view illustrating the knitting of the leg fabric.

Figures 4, 5, and 6 diagrammatically illustrate 10 the knitting and formation of the cuff of the stocking.

Figures 7 and 8 diagrammatically illustrate the knitting of the ankle portion of the boot fabric.

Figure 9 is a side elevation showing a slight 15 modification of the invention.

Figure 10 is a side elevation showing another slight modification of the invention.

Figure 11 is a diagrammatic view of a portion of that type of cuff illustrated in Figure 9. 20

Figure 12 is a sectional view through the cuff portion of the stocking illustrated in Figure 9.

Figure 13 is an elevation of the leg fabric as produced on a circular knitting machine.

Figure 14 is a view similar to Figure 13 illustrating a portion of the leg fabric cut so as to be topped onto the needles of a full fashioned 25 knitting machine.

Figure 15 diagrammatically illustrates the leg fabric of Figure 14 topped onto the needles of a 30 full fashioned knitting machine.

Figure 16 is a fragmentary portion of a slightly modified form of stocking.

Referring to Figures 1 to 8 inclusive, particularly to Figures 1 and 2, the numeral 1 designates 35 a full fashioned stocking consisting of a leg section 2 and a boot section 3, the sections being knitted from dissimilar yarns, such as silk yarn in the leg section 2 and cotton yarn in the boot section 3. The boot section 3 includes the heel 40 tabs 4 and the foot fabric 5.

At the point of juncture of the leg section 2 and the boot section 3, there is arranged a double 45 ply cuff 6 consisting of an inner ply 7 and an outer ply 8, the two plies of the cuff being also knitted from cotton yarn. The outer ply 8 of the cuff may be provided with ornamental open work, as indicated by the numeral 9 and, further, is provided with a picot edge 10.

In the knitting of the leg section, as shown in 50 Figures 3 to 8 inclusive, a silk yarn is fed to the needles 11 of the full fashioned knitting machine until the leg section 2 has been completely knitted. The feeding of the silk yarn is then discontinued and a cotton yarn is fed to the 55

needles 11 to enable the knitting of a cuff fabric 12, after which the cuff fabric is folded and topped back upon the needles of the knitting machine, as shown in Figure 6, to provide the cuff with the inner ply 7 and the outer ply 8.

After this has been accomplished, the cotton yarn continues to be fed to the needles so that the ankle portion of the boot section 3 may be knitted, which boot section includes the heel tabs 4. 10 As a final knitting operation, the heel tabs 4 and adjacent part of the ankle portion of the boot section 3 are topped in the usual way onto the needles of a full fashioned footer knitting machine and the foot fabric 5 is knitted completely from a cotton yarn. It is to be understood, of course, that other combinations of yarns may be utilized in the knitting of the leg section and boot section of the leg fabric, the cuff, and the entire foot fabric, so as to produce a contrast 15 between the various fabrics to give the appearance of a boot applied over a silk stocking.

Proceeding as outlined above, a full fashioned stocking is produced having a silk upper portion and a cotton lower portion, the cotton portion 25 being so designed and shaped as to produce a boot that is connected to the leg fabric as a continuation thereof, thereby enabling the leg fabric to hold the boot in proper shape upon the leg of the wearer and, further, enabling the leg fabric to be 30 severed from the boot for the independent use of the boot when the occasion arises. Further, it will be appreciated that the direct connection of the leg fabric and the boot fabric enables the boot fabric to be supported from the knee of 35 the wearer, thereby assuring the taut arrangement of the boot around the ankle and foot of the wearer. It will be further appreciated that the cost of manufacturing is materially reduced when compared with the separate knitting of a 40 complete silk stocking and a complete boot and, further, the life of the stocking may be extended, as the leg fabric may be severed from the boot for the independent use of the boot by the wearer.

45 It is to be understood that the leg fabric 1 may be knitted from various types of yarns and the yarns may be dyed flesh color so that the entire stocking, when in use, will produce the effect of a boot worn alone upon a bare leg.

50 Referring to Figure 9, there is illustrated a cuff 13 provided with an elastic band 14, consisting of alternating groups of courses 15 and 16 knitted respectively from elastic and non-elastic yarns.

55 Referring to Figure 10, there is illustrated an elastic band 17 directly secured to the cuff 13 by sewing one edge thereto, or by topping on,

or by any other method of manufacture. The purpose of the elastic band is to enable the cuff to cling closely around the ankle of the wearer and provide means for the proper holding of the boot around the ankle of the wearer.

5 Referring to Figures 13, 14, and 15, there is illustrated a circular knit type of leg fabric 18 that is provided with a drop stitch 19 along the rear surface thereof so as to provide a guiding line for the cutting of the fabric to lay open 10 a portion thereof, as indicated at 20, to expose in the proper manner a topping course 21. This topping course 21 is topped onto the needles 22 of the knitting machine so that the boot may be knitted on a full fashioned knitting machine. 15 The drop stitch 19 and the cut edges of the portion 20, as well as the edges of the full fashioned boot blank, are seamed in the usual manner, thereby giving the stocking the appearance of a complete full fashioned stocking.

20 In Figure 16, there is illustrated a stocking consisting of the leg fabric 23 and foot fabric or boot 24, the cuff being dispensed with. The foot fabric 24, at the point usually occupied by the cuff, is provided with a group of open work 25 courses 25 for ornamentalizing the boot portion of the stocking at its point of juncture with the leg fabric 23.

It is, of course, understood that the invention is capable of many modifications and therefore 30 we do not wish to be limited in protection except as set forth in the following claims.

What we claim is:

1. A stocking comprising, in combination, a leg section, a boot connected to the leg section, and 35 a cuff arranged at the point of juncture between said leg fabric and boot and having an elastic material incorporated therein whereby to draw the same close to the leg of the wearer.

2. A stocking comprising, in combination, a leg 40 section, a boot joined to the leg section and a cuff arranged at the point of juncture between said leg section and boot and including an elastic band affixed thereto to draw the same close to the leg of the wearer.

3. A stocking comprising a knitted leg section, a cuff knitted as a continuation of the leg section and a boot knitted as a continuation of the cuff, said cuff including elastic elements 45 whereby to draw the cuff close to the stocking.

4. A stocking comprising a leg section and a boot section, said section being knitted from dissimilar yarns, and a cuff arranged at the point of juncture of said sections, said cuff including elastic elements for increasing its elasticity.

55 JAS. UNDERWOOD.
STERLING MACK.
